UNITED STATES PATENT OFFICE.

JOHN M. LARSEN, OF CHICAGO, ILLINOIS, ASSIGNOR, BY MESNE ASSIGNMENTS, TO
CONTINENTAL MACHINERY COMPANY, OF CHICAGO, ILLINOIS, A CORPORATION OF
DELAWARE.

DESIGN FOR A CASING FOR A COMBINED CONDENSER AND FREEZER.

57,137.

Specification for Design.

Patented Feb. 22, 1921.

Application filed April 24, 1919. Serial No. 292,507. Term of patent 7 years.

To all whom it may concern:

Be it known that I, JOHN M. LARSEN, a citizen of the United States, residing at Chicago, in the county of Cook and State of Illinois, have invented a new, original, and ornamental Design for a casing for a Combined Condenser and Freezer, of which the following is a specification, reference being had to the accompanying drawing, forming part thereof.

Figure 1 is a side elevation of a casing for a combined condenser and freezer showing my new design.

Fig. 2 is an end elevation of the same.

I claim:

The new, original and ornamental design for a casing for a combined condenser and freezer, as shown.

JOHN M. LARSEN.
